CLAIM

The ornamental design for a storage bag, as shown and described.

DESCRIPTION

FIG. 1 is a front view of a storage bag showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of another embodiment of a storage bag showing our new design;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The broken lines in the figures show portions of the storage bag that form no part of the claimed design.

The dot-dash lines in the figures show boundaries that form no part of the claimed design.

1 Claim, 8 Drawing Sheets
